UNITED STATES PATENT OFFICE.

HANS MIKOREY, OF SCHÖNEBERG, NEAR BERLIN, GERMANY, ASSIGNOR, BY MESNE ASSIGNMENTS, TO MINIMAX COMPANY, OF NEW YORK, N. Y., A CORPORATION OF NEW YORK.

FIRE-EXTINGUISHER.

1,224,192.

Specification of Letters Patent.

Patented May 1, 1917.

Application filed November 7, 1910, Serial No. 591,186. Renewed October 8, 1915. Serial No. 54,890.

To all whom it may concern:

Be it known that I, HANS MIKOREY, a subject of the German Emperor, and a resident of Schöneberg, near Berlin, Kingdom of Prussia, Germany, (whose post-office address is 13 Wartburgstrasse, Schöneberg, near Berlin, Kingdom of Prussia, Germany,) have invented certain new and useful Improvements in Fire-Extinguishers, of which the following is a specification.

The present invention relates to a fire-extinguisher for manual use, the handle of which is secured to the container for the extinguishing fluid by means of an articulated joint. The essential feature of the invention consists in a part of said handle being made to serve as a part of the jet-pipe and connected with the outlet from said container by means of a flexible tube. This arrangement has the purpose to allow of sending the stream of the extinguishing liquid in an upward or downward direction on the fire without tilting the container. Corresponding to the aforesaid construction and arrangement of the handle is also the arrangement for starting the extinguisher according to the present invention provided on the bottom of the same. Fire-extinguishers are already known, in which the arrangement for starting them is fitted to the bottom of the container; in such extinguishers, however, the handle is arranged in such a manner, that the container must be tilted both for directing the stream of liquid and for moving the extinguisher into the position required, so that the pin or the like employed for starting the extinguisher can be struck against the floor. The extinguisher according to the present invention may therefore, after having been carried by the handle to the place where the fire has broken out, be started there by simply dumping it against the floor, without having to tilt it and the stream of liquid may then be directed at will upward or downward, also without any tilting of the container.

The accompanying drawing exemplifies a constructional form of the present invention.

Figure 1 shows a side elevation of the extinguisher, with a portion broken away, and,

Fig. 2 is a top plan view.

In the drawing *a* is the container of any suitable shape filled with the extinguishing

liquid, *b* is a handle attached to said container in known manner by means of an articulated joint *c* or the like. This handle is of a horseshoe shape, and its handle-bar *e* is made tubular and is fitted with a jet-pipe *g* with a nozzle *f*. In the interior of the container *a* an outlet-pipe *d* is arranged extending to a suitable point of the bottom.

In the constructional form shown in the drawing the tube *d* is arranged to emerge from the container *a* and is connected by means of a flexible tube *h* with the tubular bar *e* of the handle. This flexible tube may also be used as a substitute for the joint *c* above mentioned. In this event the said tube could be arranged between the tube *d* emerging at the center of the container head, and a passage in handle *b* leading to tube *g*.

The gas-pressure for forcing the extinguishing liquid out of the container may be produced in any suitable manner. If the gas pressure is to be produced by chemical means, the cage *i* or the like in which one or several cartridges are arranged containing chemicals and to be opened in known manner by a percussion pin *k* or the like, is preferably arranged in known manner at the bottom of container *a*.

By such arrangement it is possible to operate the extinguisher with one hand only and to keep it working notwithstanding the direction of the stream of liquid being changed according to the requirements. With this extinguisher it will be possible to send the stream of liquid in a vertical direction either upward or downward. The directing of the stream is effected by means of the movements of the handle, the container hanging always vertically below the handle. As furthermore the extinguisher can be operated with the arm of the operator hanging straight down, his hand will not be fatigued.

The handle *b* is preferably fitted with four feet *m*, and the joint *c*, if any, is arranged so as to allow of being rigidly fixed, so that the extinguisher may be stood up in an inverted position on said handle, say for charging or filling. The extinguisher may also be permanently kept in such position, for the purpose of avoiding the liquid being forced out by expansion of the air or an increase of the inner pressure from other causes, as the inlet opening of the tube *d* will in such position be above the level of

the liquid and the air in the container is in direct communication with the atmosphere.

I claim:

1. In a fire extinguisher, the combination of a container, an outlet tube for discharging the liquid contents of said container, a handle, a tube within the cross bar of this handle, a discharge nozzle connected to said handle tube, an articulated joint connecting the handle to the top of the said container, a flexible tube connecting said handle tube to the outlet tube of the container, a closed vessel containing and comprising means for the liberation of gas, and a device for opening said vessel and arranged at the bottom of the container, substantially as described and for the purpose specified.

2. In a fire extinguisher, the combination of a container, an outlet tube for discharging the liquid contents of said container, a handle provided with feet, a joint connecting said handle with the top of said container and allowing to be rigidly fixed, a tube within the cross bar of the handle, a discharge nozzle connected to said handle tube, a flexible tube connecting said handle tube to the outlet of the container, and a device for opening said vessel and arranged at the bottom of the container, substantially as described and for the purpose specified. 30

HANS MIKOREY.
